UNITED STATES PATENT OFFICE.

REYNOLD JANNEY, OF WESTBOROUGH, MASSACHUSETTS.

DESIGN FOR A FOOT-PIECE FOR PEDALS.

SPECIFICATION forming part of Design No. 26,412, dated December 15, 1896.

Application filed July 18, 1896. Serial No. 599,740. Term of patent 7 years.

To all whom it may concern:

Be it known that I, REYNOLD JANNEY, a citizen of the United States, residing at Westborough, in the county of Worcester and State 5 of Massachusetts, have invented a new and useful Design for Foot-Pieces for Bicycle-Pedals, of which the following is a specification.

My design relates to a **U**-shaped foot-piece 10 for pedals.

In the accompanying drawings, forming part of this application, Figure 1 is a perspective view of a foot-piece for pedals embodying my design, and Fig. 2 is an end elevation 15 thereof.

The leading feature of my design resides in the character of ornamentation applied to the side bars of a yoke or **U**-shaped tread-piece for bicycle-pedals. This ornamentation is 20 distinguished from tread-pieces provided simply with a series of perforations or from tread-pieces having diamond-shaped openings, giving the same the character of a grating, principally by comprising alternate circular and 25 substantially hour-glass perforations, giving said side bars a foraminated or open-work appearance.

Referring to the drawings and in detail, A and B designate the side bars of a foot-piece 30 for bicycle-pedals embodying my design. At its end the side bar B is provided with an inclined rib or section terminating in a downwardly-extending stop 11, and the side bar A is provided with a similar inclined rib or sec-

tion 16, terminating in an upwardly-extending stop 10. The side bars A and B are provided on their upper edges with teeth 14 and on their lower edges with teeth 15. A foraminated or open-work appearance is given to the side bars A and B by means of circular 40 holes 18 and intermediate cut-away portions or holes 19, which are arranged to leave curved struts or connecting-pieces 17.

The central part of the **U**-shaped tread-piece for bicycle-pedals embodying my design 45 is provided with an upwardly-extending stop 12 and a downwardly-extending stop 13, and is given an open-work or foraminated appearance by means of the cut-away portions or orifices 22, 23, and 24, which are arranged to 50 leave connecting ribs or struts 20 and 21.

By this design the foot-piece can be stamped out of metal and bent to the desired form, and the configuration presented is an attractive one, the foraminated or open-work appearance of the foot-plate being produced almost entirely by curved lines. 55

What I claim, and desire to secure by Letters Patent of the United States, is—

The design for a foot-piece for bicycle-pedals, substantially as shown and described. 60

In testimony whereof I have hereunto set my hand in the presence of two subscribing witnesses.

REYNOLD JANNEY.
